[57] **CLAIM**

The ornamental design for a combined fish scaler, bottle opener and hook degouger or the like, as shown.

DESCRIPTION

FIG. 1 is a top perspective view of a combined fish scaler, bottle opener and hook degouger or the like showing my new design;

FIG. 2 is a bottom perspective view thereof;

FIG. 3 is a top plan view thereof;

FIG. 4 is a side elevational view thereof;

FIG. 5 is a left end elevational view thereof;

FIG. 6 is a bottom plan view thereof;

FIG. 7 is a right end elevational view thereof; and

FIG. 8 is a side elevational view opposite that shown in FIG. 4.
